UNITED STATES PATENT OFFICE.

JAMES W. SHARBUTT, OF TROY, TEXAS, ASSIGNOR OF ONE-HALF TO C. A. MAEDGEN,
OF TROY, TEXAS.

GARMENT-SECURING MEANS FOR BELT BUCKLES.

Application filed June 9, 1923. Serial No. 644,333.

To all whom it may concern:

Be it known that I, JAMES W. SHARBUTT, a citizen of the United States, residing at Troy, in the county of Bell and State of Texas, have invented certain new and useful Improvements in Garment-Securing Means for Belt Buckles, of which the following is a specification.

In carrying out the present invention it is my purpose to provide a means whereby the belt buckles of trousers supporting belts may be secured to the trousers in a novel and simple manner for precluding the slipping of the buckles to one side of the front 15 of the trousers or above the same.

The primary object of this invention resides in the provision of a belt buckle wherein the same is formed or otherwise equipped with one member of a separable fastener 20 adapted with which another member of a separable fastener is carried by the garment, the two members adapted to be so connected for functioning as above described.

The nature and advantages of the invention will be better understood when the following detailed description is read in connection with the accompanying drawings, the invention residing in the construction, combination and arrangement of parts as 30 claimed.

In the drawings forming part of this application, like numerals of reference indicate similar parts in the several views, and where in:-

35 Figure 1 is a rear elevation of the belt buckle equipped with one member of a separable fastener.

Figure 2 is a fragmentary front elevation of a pair of trousers provided with 40 the other member of a separable fastener, and,

Figure 3 is a cross-section through the buckle and trousers showing the elements of the fastener joined.

45 Referring to the drawing in detail 5, designates a belt buckle frame of any desirable form and having a loop 5' mounted thereon. In the furtherance of my invention the inner side of this buckle 5 is preferably formed with a female member 6 of a well known type of separable fastener, it being, however, understood that this member may be a separable part of the buckle and secured thereto in any suitable manner. This mem-

ber 6 is preferably disposed within a pocket 55 7 formed in the inner side of said buckle 5 for consequently allowing the buckle to have close contact throughout its longitudinal surface with the garment.

In Figures 2 and 3, 8 designates generally 60 a pair of trousers which carries at its front side the male member 9 of the said female fastener, it being within the scope of this invention to provide this member of said fastener upon a button element 10 that engages 65 through buttonholes of the garment for maintaining the usual opening in the front side thereof closed.

In view of the above description it will 70 at once be apparent that after the belt which carries the buckle 5 has been adjusted around the waist of the wearer the buckle 5 is moved to a position directly forwardly of the male element 9 of the separable fastener whereby the same may be inserted within the female 75 member 6 of the buckle for consequently preventing any movement of the same.

Numerous advantages of the device of this character will be readily appreciated and even though I have herein set forth the most 80 practical embodiment to the invention with which I am familiar it is nevertheless to be understood that minor changes may be made therein without departing from the spirit and scope as claimed.

Having described my invention, what I 85 claim and desire to secure by Letters Patent, is:-

A garment belt structure comprising a strap, a buckle frame applied to the strap 90 and having a loop, there being slots provided at the upper and lower sides of the frame and located under the loop and disposed at acute angles to the inner surface of the loop, the frame being provided at its inner wall 95 with an upstruck portion, the surface of which is approximately parallel with the side edges of the slots, a pin movably mounted in the slots and disposed transversely across said upstruck portion of the 100 frame, and a female securing member applied to the outer surface of the angularly disposed wall of the upstruck portion of the frame and adapted to engage a securing device carried by the garment.

105 In testimony whereof I affix my signature.

JAMES W. SHARBUTT.
